UNITED STATES PATENT OFFICE

PHILIP A. FRAZIER, OF CHICAGO, ILLINOIS, ASSIGNOR TO R. R. DONNELLEY & SONS CO.,
A CORPORATION OF ILLINOIS

BOOKBINDING MACHINE

Application filed May 28, 1927. Serial No. 194,949.

This invention relates to improvements in book binding machines of the type in which the edges of the sheets at the back of the book are cut away and which are then secured together by means of glue or the like which also serves to hold a cover thereon.

Various means have been suggested for roughening the cut edges of these sheets to make them receive and hold the glue more firmly. An object of this invention however is to provide means for placing the cut edges of the sheets to one side so as to place them in overlapping relation to each other and applying glue to these edges while in this overlapping position. In this way some glue is applied to the sides of the sheets as well as to their edges so that when the sheets are again brought back to their normal mid-position some glue will be found to lie between the sheets themselves so that a hold is obtained on the sheets along a narrow margin on the faces of the sheets, whereas, heretofore the sheets came in contact with the glue only solely on their edges.

This and other objects, as will hereinafter appear, are accomplished by this invention which is fully described in the following specification and shown in the accompanying drawings, in which:

Figure 1 is a partial side elevation of a conveyor in a book binding machine carrying books over a gluing wheel having teeth in the form of a herring-bone;

Fig. 2 is a section of the same on the line 2—2 of Fig. 1;

Fig. 3 is a top plan view of a modified form of the device; and

Fig. 4 is a section on the broken line 4—4 of Fig. 3.

This invention is an improvement on the book binding machine shown in the patent to Bredenberg, No. 1,073,324, granted September 16, 1913, and may be similar thereto except in the particulars which are herein shown and described.

The embodiment illustrated comprises a chain made up of links 10 which are pivotally connected at their ends and carried upon rollers 11 and 12 which operate in guide channels 13 and 14. The links 10 consist of flat

plates and opposite of each of these is another flat plate 15 which carries at its ends pins 16 and 17 which have heads 16a beneath each of which rests a compression spring 18 which serves to normally press the plates 10 and 15 toward each other.

As the books enter the machine in the form of signatures which are folded in any well known manner, the plate 15 is drawn back compressing the springs 18 so that the books A consisting of a bunch of signatures may be inserted. As explained in the above mentioned patent, the spring 18 is then permitted to draw the plate 15 down so as to grip the book A. The back of the book A is then cut in any well known manner as explained in this patent and the book then passes to the gluing wheel as shown in Fig. 1.

The embodiment shown in Figs. 1 and 2 comprises a double wheel 19 having oppositely inclined spiral teeth which are pressed in the form of a herring-bone gear and which are carried upon a shaft 20 which is suitably journaled in a glue pot 21. The gear 19 is placed beneath the path of the books A and preferably with the center of the herring-bone gear 19 near the center of the books A with the shaft 20 extending substantially at right angles to the path of the books.

The books A and the upper portion of the wheels 19 are advanced in the same direction and at substantially uniform rate, but the books A will advance somewhat faster so that as the sheets of the book A pass over the herring-bone wheel 19 they will have a tendency to be spread outwardly by the spiral teeth as shown in Fig. 2, thereby causing the edges of the sheets in contact with the wheel to assume an overlapping relation with respect to the adjacent sheets so that a narrow margin of each sheet will be uncovered so that the ones in contact with the glue which is picked up by the wheel 19 from the mass of glue B in the bottom of the glue pot 21.

Thus it will be seen that I have provided a simple and effective means for applying glue to the narrow overlapping margins of sheets so that when these sheets are again brought back to their normal overlapping position some glue will be carried in between the sheets

thereby greatly strengthening the book because the sheets are now glued to each other along narrow margins whereas by the method heretofore used adhesion took place principally between the edges of the sheets and the glue.

5 Figs. 3 and 4 show another embodiment of the invention in which two-toothed wheels 22 and 23 are carried upon shafts 24 and 25 which are suitably journalled in the sides of the glue pot 26 and carry bevel gears 27 and 28 respectively. These gears mesh with a bevel gear 29 which is carried on a vertical shaft 30 and driven in timed relation to the 10 mechanism which drives the book conveyor which may be of the type shown in Figs. 1 and 2.

The path of the books is shown as C and the books, shown in Fig. 4 as D are held by 20 the plate 10^a and 15^a of the conveyor.

The toothed wheels 22 and 23 are preferably provided with straight teeth, these 25 wheels being set at oppositely inclined angles. As the book D passes across the top of the toothed wheel 22, the sheets are deflected to one side as shown in Fig. 4, the wheel in this case preferably running at a somewhat greater speed than that of the book and carrying glue which is picked up from the body of the 30 glue E in the glue pot 26.

As shown in Fig. 4, the sheets at the left hand side are preferably spread and "fanned" somewhat more than those at the right hand side of the book D. Consequently a second 35 wheel 23 is provided which may, if desired, be narrower than that of the wheel 22 and which serves to spread out or "fan" the right hand sheets of the book D, this wheel also simultaneously applying glue to the overlapping 40 margins of the sheets.

Thus it will be seen that a very simple and effective means is provided for applying glue to the margins of adjacent sheets so as to increase the bond between these sheets and the 45 adjacent sheets thereby providing a much stronger book and one which will be able to withstand much more rough usage than those which have heretofore been made by gluing the sheets to the cover.

50 While I have shown and described but two embodiments of this invention, it is to be understood that it is capable of many modifications. Changes therefore in the construction and arrangement may be made which do 55 not depart from the spirit and scope of the invention as disclosed in the appended claims.

I claim:

1. The method of gluing the edges of books consisting of bending back the edges of the 60 sheets to cause them to assume an overlapping position with respect to adjacent sheets, applying glue to said overlapping edges while in said overlapping position and permitting said sheets to return to normal position before the glue has set whereby glue will cause the 65

overlapping portions to adhere to adjacent sheets when the sheets return to the normal position.

2. In mechanism for gluing the edges of books and the like preparatory to binding, 70 means for moving the books endwise, and means in the path of said books and bearing thereon for causing said sheets to be deflected so as to assume an overlapping position with respect to adjacent sheets and for simultaneously applying glue thereto. 75

3. In mechanism for gluing the edges of books and the like preparatory to binding, means for moving the books endwise, a toothed wheel in the path of said books and bearing thereon for causing said sheets to be deflected from the normal overlying position so as to cause them to assume an overlapping position with respect to adjacent sheets and for simultaneously applying glue thereto. 80 85

4. In mechanism for gluing the edges of books and the like preparatory to binding, means for moving the book endwise, a toothed wheel having teeth set diagonally with respect to the path of said books and bearing 90 thereon for causing said sheets to be deflected so as to assume an overlapping position with respect to adjacent sheets and for simultaneously applying glue thereto.

5. In mechanism for gluing the edges of 95 books and the like preparatory to binding, means for moving the books endwise, a toothed wheel dipping in glue and lying in the path of said books and bearing thereon for causing said sheets to be deflected so as to assume an overlapping position with respect to adjacent sheets and for simultaneously applying glue thereto. 100

6. In mechanism for gluing the edges of books and the like preparatory to binding, 105 means for moving the book endwise, a toothed wheel having teeth set diagonally with respect to the path of said books and bearing thereon for causing said sheets to be deflected so as to assume an overlapping position with 110 respect to adjacent sheets and for simultaneously applying glue thereto, and means for driving said wheel at a different speed from that of the books.

7. In mechanism for gluing the edges of 115 books and the like preparatory to binding, means for moving the books endwise, and a plurality of toothed wheels having teeth set diagonally with respect to the path of said books and bearing thereon for causing said 120 sheets to be deflected so as to assume an overlapping position with respect to adjacent sheets and for simultaneously applying glue thereto.

8. In mechanism for gluing the edges of 125 books and the like preparatory to binding, means for moving the books endwise, a plurality of toothed wheels having teeth set diagonally with respect to the path of said books, one of said wheels tending to deflect 130

and to spread outwardly the sheets on one side
of said books, the other tending to deflect and
to spread outwardly the sheets on the other
side of said books, said wheels carrying glue,
5 and means for driving said wheels at a dif-
ferent surface speed from that of said books.

In testimony whereof I have hereunto set
my hand this 23rd day of May, 1927.
PHILIP A. FRAZIER.
